UNITED STATES PATENT OFFICE.

RAYMOND M. ANDERSON, OF CHICAGO, ILLINOIS, ASSIGNOR TO STROMBERG MOTOR DEVICES COMPANY, OF CHICAGO, ILLINOIS, A CORPORATION OF ILLINOIS.

CARBURETER.

1,311,307.

Specification of Letters Patent. Patented July 29, 1919.

Application filed April 30, 1915. Serial No. 24,849.

To all whom it may concern:

Be it known that I, RAYMOND M. ANDERSON, a citizen of the United States, residing at Chicago, in the county of Cook and State 5 of Illinois, have invented a certain new and useful Improvement in Carbureters, of which the following is a full, clear, concise, and exact description, reference being had to the accompanying drawings, forming a 10 part of this specification.

My invention relates to carbureters for internal-combustion engines, and has for its object improved means for creating and maintaining the most desirable mixture 15 portions for the varying demands of the engine with which the device is connected.

In the prior art great difficulty has been encountered in attempts to provide means for getting the proper rich mixture on starting and low running without interfering 20 with the action of the carbureter upon the higher speeds. This difficulty has been due mainly to the fact that upon low suction the reduction in pressure is sufficient to lift 25 the liquid hydrocarbon which is used for fuel out of the fuel-nozzle which is provided, as is well known in the art, but is insufficient to take all of this fuel to the engine. The result is that the supply of the 30 liquid hydrocarbon, such as gasoline, is insufficient on starting and low running so far as that which actually goes to the engine is concerned, while, as a matter of fact, the amount of fuel really lifted out of the 35 nozzle would be sufficient. This gasoline which is lifted out of the nozzle but which does not get to the engine settles on the sides of the carbureting chamber and collects where opportunity affords, and then, when 40 the higher suctions are attained, this collected fuel goes to the engine with the regular supply from the nozzle, making the supply of gasoline on the higher suctions too great. This detrimental action is commonly 45 called "loading."

My invention is intended to eliminate both difficulties. That is, it provides the rich mixture upon starting and low running and at the same time prevents collection of 50 the fuel in the carbureting chamber which, in turn, prevents loading. These results are accomplished by providing a passageway which leads from the fuel nozzle to a point above the throttle-valve which controls the 55 passage to the engine. This fuel passage

way actually extends into the fuel-nozzle and in this the two functions are effectively accomplished. Upon starting and low running the suction is concentrated upon the gasoline in the nozzle, so that a rich mixture 60 is the result, the air being properly limited, and during this low-suction period, since this special passageway robs the nozzle of its gasoline, there will be no issue, or substantially no issue, into the carbureting 65 chamber below the throttle. In this way, the carbureting chamber is kept dry and no chance for loading is created.

My invention is illustrated in the accompanying drawings, in which:

Figure 1 is a vertical axial sectional view, and,

Fig. 2 is a vertical axial sectional view showing the fuel-nozzle in detail and on a larger scale.

The casing 1 is provided with an air-inlet 2 and a mixture-outlet 3, the latter being surrounded by a flange 4, which may be secured to the manifold of an internal-combustion engine. The air-inlet 2 may be supplemented by openings 5—5 in the sides of the air-inlet pipe, which openings may be controlled by the rotatable valve 6 so as to regulate the admission of air. A passageway, as is well understood, connects the air-inlet and the mixture-outlet; and a Venturi tube 7 is secured in the vertical portion of this passageway, as shown. This Venturi tube forms the mixing-chamber 8. The carbureting-chamber is surrounded by a water-jacket 9, which is provided with inlet and outlet-pipes 10—10.

At the side of the casing 1 a shelf 11 is provided, and a float-chamber 12 with the cover 13 is mounted upon this shelf. A 95 valve-seat member 14 is provided in the center of the shelf and is provided itself with a central passageway 15, through which gasoline may enter the float-chamber. The shelf is provided at the bottom with a pocket 100 16, in which a union 17 is disposed, this union being connected by means of piping 18 with the gasoline supply.

A valve 19 co-operates with the valve-seat at the top of the member 14, this valve 19 105 being mounted for reciprocating movement. By means of the levers 20—20, which are pivoted at 21—21, this valve is mechanically connected with the float 22. The gasoline which enters by way of the passageway 15 110

passes into the float-chamber by way of the small openings 23-23, and the float mechanism operates, as is well known in the art, to maintain a constant level of the gasoline. 5 This level is maintained at approximately the dot-and-dash line X-X.

The nozzle is illustrated at 24. It will be seen that this structure is generally tubular in shape and is disposed in axial alinement 10 with the vertical part of the passageway through the casing. In other words, this nozzle is disposed concentrically with the Venturi tube, and the upper end of the nozzle terminates at a point slightly above the 15 most restricted portion of the Venturi tube. The nozzle is provided with an interior partition 25, which is clamped in place by a plug 26, and a tube 27 extends from the top of the nozzle downwardly concentrically 20 with the partition 25 and through an opening in the plug 26. The bottom of the tube 27 is lodged in a plug 28 which, in turn, is threaded in another plug 29, screwed into the port 30 leading from the pocket 31. The 25 pocket 31 is connected with the float-chamber by means of a passageway 32.

It will now be seen that the opening in the plug 26 is considerably larger than the tube 27, so that there will remain a space 33 30 surrounding the tube for the passage of the gasoline. The gasoline can then pass upwardly through the annular space between the partition 25 and the tube 27 and out of the openings 34-34 at the top of the nozzle. This is clearly shown in Fig. 2.

It will be seen that at the bottom of the partition 25 openings 35-35 are provided, these openings leading into the annular space surrounding the partition. This annular space, by means of openings 36-36, is connected with an accelerating well 37, which is cored in the casting and which at the top is open to the atmosphere by means of the restricted port 38. It will be 45 seen that under conditions of no suction the gasoline will stand at a common level in the float-chamber, the accelerating well 37 and the nozzle 24. It will be seen that below the normal level of the fuel the tube 27 is 50 provided with openings 39-39, and that at the top of the partition 25 openings 40-40 are provided.

It will now be clear that when the throttle is closed, or nearly closed, that is, when it 55 is closed as far as it can be, leaving a leak therethrough or therearound—practically all of the suction, except that which is satisfied by the limited passage of air, is concentrated upon the nozzle 24 by means of the tube or by-pass 41, which is carried upon a stud 42, mounted in an opening 43 in the throttle 44, which, in turn, is mounted upon the shaft 45, which is adapted to be turned by the operator in any suitable manner.

65 The tube or by-pass 41 extends down and

into the nozzle 24, as illustrated, and at the top an outlet 46 is provided. It will be seen that the tube 41 is in such position that when the throttle is opened by clockwise rotation, the tube will be made to extend down farther 70 into the nozzle 24. It will be seen that when the throttle is in its closed position, a bleeder opening 47 in the tube 41 is exposed above the nozzle 24, this being clearly illustrated in Fig. 2. This permits the entrance of a 75 slight amount of air to partly satisfy the suction concentrated upon the outlet opening 46. In the main, however, the idea is to concentrate the suction which is transmitted down from the opening 46 upon the 80 nozzle 24, in such a manner as to carry sufficient gasoline to the engine to produce a rich mixture and at the same time to prevent any issue, or substantially any issue, through the openings 34-34, the operation 85 being in the nature of robbing the nozzle 24 of its gasoline so that it cannot feed into the Venturi tube under these conditions of low suction. All the gasoline that is taken out of the nozzle is carried up beyond the 90 throttle, where it produces the rich mixture. The provision of the bleeder opening 47 is a refinement which may or may not be desirable, dependent upon the conditions. If the passage of air past the throttle when 95 the throttle is closed as far as it can be is insufficient, this bleeder is necessary; and, on the other hand, the bleeder is unnecessary if sufficient air can pass the throttle in its closed position to create the proper mixture 100 and satisfy the suction to the proper extent. Since on these conditions of low suction the gasoline is all carried up through the bypass, there is no possibility of loading, since there is no issue from the openings 34-34—105 the regular nozzle outlets—to provide gasoline which could collect in the carbureting chamber. The result is that the chamber is kept dry and subsequent loading prevented. As the nozzle 24 is subjected to the higher 110 suction, however, the issue from the openings 34-34 begins, but at such a time the suction is sufficient to carry all the gasoline which issues in this way to the engine. As the throttle is opened, the by-pass 41 gradually loses its effectiveness, and, finally, its functioning is negligible, if, indeed, it functions at all. The transfer from the by-pass supply to the regular nozzle supply is made more gradual by the provision of the proper 120 supply at starting, with the inclusion of the bleeder 47. As the throttle is opened the bleeder 47 moves downwardly into the tube 27 and thus their action is removed, concentrating all the remaining suction on the 125 nozzle, without bleeding. If the suction at 46 in these subsequent stages is less, the effect of the by-pass upon the nozzle is less and it will be seen that the automatic cutting out of the bleeder extends the effectiveness 130

of the by-pass to such an extent that the transfer of the fuel-supply from the by-pass to the regular nozzle opening will be very gradual. In this accelerating period the 5 regular fuel supply from the float-chamber up through the annular space between the partition 25 and the tube 27 is augmented by the supply of fuel from the accelerating well 37, which passes upwardly through the annular space between the wall of the nozzle 24 and the partition 25, passing inwardly through the openings 40-40 and then upwardly and out of the openings 34-34. This provides the desirable increase of fuel 10 upon the increased demand of the engine, and at the same time is such that, as the suction increases, the flow of fuel will not become too great, since after the well 37 is exhausted the supply is limited to what can 15 pass upwardly directly from the float-chamber, as has been described. If the engine continues, there is no opportunity for the well 37 to be filled, but when it comes to rest or comes to an idling condition, removing 20 suction from the openings 34-34, the well will fill and thus be ready for the next increase in demand.

After the well 37 has become emptied, the air entering the restricted passageway 38 25 will pass upwardly through the nozzle and will displace some of the gasoline so as to partly retard the gasoline supply and thus prevent abnormal increase in the issue of gasoline.

35 I claim as new and desire to secure by Letters Patent of the United States:

1. In a carbureter, a carbureting chamber having an air-inlet and a fuel-outlet, a butterfly throttle valve controlling said outlet, a fuel-nozzle leading into said carbureting chamber, and a by-pass carried by said 40 throttle, leading from the interior of said nozzle to and through the throttle.

2. In a carbureter, a carbureting chamber 45 having an air-inlet and a fuel-outlet, a throttle valve controlling said outlet, a fuel-nozzle leading into said carbureting chamber, and a by-pass leading from the interior of said nozzle to a point above the throttle, said 50 by-pass being hung from a shaft set in said throttle.

3. In a carbureter, a carbureting chamber having an air-inlet and a fuel-outlet, a throttle valve controlling said outlet, a fuel nozzle leading into said carbureting chamber, and a by-pass leading from the interior of 55 said nozzle to a point above the throttle, said

by-pass at its upper end being coiled about a shaft set in said throttle and having its outlet feeding to the engine side of the throttle when the throttle is in closed position. 60

4. In a carbureter, a carbureting chamber having an air-inlet and a fuel-outlet, a throttle valve controlling said outlet, a fuel-nozzle leading into said carbureting chamber, and a by-pass leading from the interior of said nozzle below the restricted feed-outlet thereof, to a point above the throttle, said by-pass at its upper end being coiled about a shaft set in said throttle and having its 70 outlet feeding to the engine side of the throttle when the throttle is in closed position.

5. In a carbureter, a carbureting chamber having an air-inlet and a fuel-outlet, a throttle valve controlling said outlet, a fuel-nozzle leading into said carbureting chamber, and a by-pass leading from the interior of said nozzle to a point above the throttle, and a bleeder in said by-pass, and means for closing said bleeder by the opening of the 75 throttle.

6. In a carbureter, a carbureting chamber having an air-inlet and a fuel-outlet, a throttle valve controlling said outlet, a fuel-nozzle leading into said carbureting chamber, a by-pass leading from the interior of said 80 nozzle to a point above the throttle, said by-pass being hung from a shaft set in said throttle, and a bleeder in said by-pass, said bleeder being arranged to pass within the 85 nozzle when the throttle is opened.

7. In a carbureter, a carbureting chamber having an air-inlet and a fuel-outlet, a throttle valve controlling said outlet, a fuel-nozzle leading into said carbureting chamber, 90 said nozzle having a central chamber, an intermediate chamber and an outer chamber, said central chamber being connected to a point above the throttle and being fed from said intermediate chamber, said intermediate 95 chamber leading directly from the supply to the nozzle outlet, and said outer chamber being fed from said intermediate chamber and connected with a well communicating with the atmosphere, said outer chamber feeding 100 into said intermediate chamber from the top thereof under suction.

In witness whereof, I hereunto subscribe my name this 27th day of April A. D. 1915.

RAYMOND M. ANDERSON.
